EMERGENCY LINK

Hyman Gerstein, Hartford, Conn.

Application May 17, 1934, Serial No. 726,127

2 Claims. (Cl. 59—85)

My invention relates to emergency links for tire chains.

It has among its objects to provide an improved emergency link and, more particularly, such a link which is long-lived and adapted to increase the traction effect of the chain. Further objects of my invention are to provide such an improved link which may be readily and quickly connected while being both very strong and also adapted to be manufactured at small expense. These and other objects of my invention will, however, hereinafter more fully appear.

In the accompanying drawing I have shown for purposes of illustration, one embodiment which my invention may assume in practice.

In the drawing,—

Figure 1 is a top plan view of a link constructed in accordance with my improvement, the same being shown in open position;

20 Figure 2 is a side elevation of this link;

Figure 3 is a bottom plan view of the same;

Figure 4 is an end view of the same;

25 Figure 5 is a view corresponding to Figure 1 but showing the link in closed position;

Figure 6 is a side elevation of the structure shown in Figure 5, and

Figure 7 is an end elevation of the same.

In this construction I have shown a link comprising a single length of wire bent generally into the shape of an S and having improved features hereinafter described.

Considering first the open form of the link, it will be noted that the latter comprises a body portion 1 in the form of a diagonally disposed substantially straight length of suitable wire having rounded oppositely disposed curved portions 2 and 3 at the opposite ends thereof and disposed in the same plane therewith. Leading upward from these portions 2 and 3 and forming continuations thereof are arcuate portions 4 and 5. These portions 4, 5 are herein inclined relative to the portions 2 and 3 in such manner as to raise the portions 4 and 5 above the plane of the portions 1, 2 and 3, as illustrated in Figure 2, i. e. so that the ends of the portions 4 and 5, remote from the portions 2 and 3, are substantially higher than the top surface of the portion 1. On the extremities of these portions 4 and 5 are further provided end portions 6 and 7 which are extended oppositely across the portion 1 above the same. More particularly, it will be noted that the portion 6 extends angularly upward from the upper end of the portion 5 and across the portion 1 in such manner as with the portions

extends similarly but in an opposite direction relative to the portion 4 in such manner as with the portions 1, 2 and 4 to form a loop 9. Moreover, it will be noted that the portions 6 and 7 are spaced apart from one another and from the body portion 1 sufficiently to permit the looped ends of a severed chain to be passed thereover and enter the loops 8 and 9.

In use, after the severed chain ends have been thus connected, the end portions 6 and 7 are 10 suitably bent down, as with pliers, or by stepping on these ends, or hammering them, or by the weight of the car, as may be most convenient. By this pressing down action it will be noted that, as shown in Figure 5, these end portions 15 are not only brought closer to the body portion 1, but closer together, as shown in Figures 5, 6 and 7, as contrasted with Figures 1, 2 and 3, all in such manner as effectually to prevent the release of adjacent chain ends from the loops 8 20 and 9. Further, the portions 4, 5 are somewhat lowered as shown in Figure 6 while the portions 2, 3 are somewhat raised as shown in Figure 7. Further it will be noted that in this position the portions 6 and 7 form, in effect, spaced cross bars 25 over the top or outer surface of the portion 1 while still having their ends extending angularly relative to one another and the portion 1 above the latter.

As a result of my improved construction, it is 30 found that at the same time that the connected chain ends are securely held together, the end portions 6 and 7 provide effective traction increasing means. Moreover, their structure and that of the adjacent portions 4, 5 is such as to 35 assist in preventing lateral skidding. After a longer period of use the end portions 6, 7 also tend to rest upon the upper surface of the portion 1 in such manner as effectively to continue their several functions. As regards wear, it will 40 also be evident that the extremities of the portions 6 and 7 absorb a large part of the wear through minimizing contact with the portions 2 and 3, full wear only coming on these portions 2 and 3 when the portions 6 and 7 are worn down. 45 Moreover, it will be noted that when the portions 6 and 7 are so worn off, the loops 8 and 9 are still maintained with the portions 4 and 5 then tending to move into the plane of the body 1.

Attention is also directed to the fact that in my 50 improved construction approximately double the normal amount of material has to be worn through before the link will yield, so that the link is very long-lived in service; all while, of course, also increasing the traction and acting to 55

5 1, 3 and 5 to form a loop 8, while the portion 7

prevent skidding as brought out above. It will also be evident that the link, being made of a single length of wire and capable of being formed in a usual forming machine, is capable of being manufactured at small expense. These and other advantages of my improved construction will, however, be apparent to those skilled in the art.

From the foregoing it will be apparent that the outer opposed sides of the free end portions 10 6 and 7 are normally spaced, as shown in Figs. 1 and 5, and extend diagonally across their respective ends of the relatively straight body portion 1 and on the same side of said body portion. Also, that the extremities of the free end portions 15 6 and 7 are bent upward in opposite directions when said free end portions are bent into substantial contact with the respective ends of the body portion 1, as shown in Figs. 5 and 6. Opening of the loops formed by the curved portions 20 2 and 3 and their free end portions 6 and 7, under abnormal strains applied to the loops in use, is thus prevented as, under such conditions, the outer opposed sides of the free end portions 6 and 7 will be brought into cooperative abutting relationship, across the relatively straight body portion, which extends diagonally between said end portions.

While I have in this application specifically described one embodiment which my invention may 30 assume in practice, it will be understood that this form of the same is shown for purposes of illustration and that the illustrative construction may be modified without departing from its spirit or the scope of the appended claims.

What I claim as new and desire to secure by Letters Patent is:

1. An emergency link for tire chains or the like comprising a length of wire bent into substantially 35 S-shape having a relatively straight cen-

tral body portion, and loops at the opposite ends of said body portion, the free end portions of said loops extending in opposite directions across their respective ends of said body portion and on the same side thereof in normal spaced relation therewith, whereby said end portions may be readily connected to adjacent chain ends and bent into substantial contact with the ends of said body portion, in which latter position the extremities of said loop end portions are upturned 10 in opposite directions and so disposed as to be brought into cooperative abutting relationship, across the relatively straight central body portion, under abnormal strains applied to said loops.

2. An emergency link for tire chains comprising 15 a rod bent to provide a loop at each end of a substantially straight intermediate portion, the outer sides of the free end portions of the loops being in spaced opposed relation and said intermediate portion extending diagonally across said 20 free end portions of the loops to space said loops and provide a tire engaging and positioning portion beyond the loops, the free end portion of each loop being normally bent upwardly out of the plane of said intermediate portion and spaced 25 therefrom on the same side portion to provide a substantial diagonally extending space between said loop free end portions which will not intersect said loops, whereby the free end portions of said loops may be bent into substantial contact 30 with said intermediate portion adjacent its respective ends so as to be supported out of contact with the tire and provide transverse traction increasing elements, and the opposed outer sides of the free end portions will be brought into abutting relation, on said intermediate portion, and prevent opening of the loops when abnormal strains are applied thereto.

HYMAN GERSTEIN.
